UNITED STATES PATENT OFFICE.

FERDINAND M. EUGENE BLASS, OF EAST ORANGE, NEW JERSEY.

SELF-HEATING SMOOTHING-IRON.

1,393,423.

Specification of Letters Patent.

Patented Oct. 11, 1921.

Application filed May 20, 1919. Serial No. 298,387.

To all whom it may concern:

Be it known that I, FERDINAND M. EU-
GENE BLASS, a citizen of the German Repub-
lic, residing at East Orange, in the county
5 of Essex and State of New Jersey, have
invented certain new and useful Improve-
ments in Self-Heating Smoothing-Irons, of
which the following is a specification.

This invention relates to improvements in
10 laundry, dressmakers' and like appliances,
made from suitable material collectively
known as sad, or flat irons, hereafter briefly
called iron, adapted for manual operation
in smoothing and pressing the surface of
15 textile or similar articles of personal and
domestic use.

The principal object is to provide an im-
plement of this character, having a con-
ventionally shaped exterior and operated in
20 the usual manner, but combined with an
effective heating means and divided inter-
iorly into compartments through which the
heat is caused to pass sinuously, thereby
conserving and utilizing it to the fullest ex-
25 tent possible, by reducing loss of heat by
waste and radiation.

Another object is to provide a shutter au-
tomatically closing the openings at such
times as the heater may be removed, thus
30 preventing loss of heat, the shutter also
operating as a latch or slide positively lock-
ing the heater to the iron when in operative
position.

These and other objects are attained by
35 the novel construction and combination of
parts hereinafter described and shown in
the accompanying drawings, forming a ma-
terial part of this specification, and in
which:—

40 Figure 1 is a partial side elevation and
vertical sectional view, the section being
taken on line 1—1 of Fig. 2, showing iron
made in accordance with the invention and
burner for natural and artificial gas.

45 Fig. 2 is a rear end and sectional view
taken on line 2—2 of Fig. 1.

Fig. 3 is a rear end elevational view of
Fig. 1 with gas burner in position. The
burner shown here has two outlets.

50 Fig. 4 is a side elevation, showing, in
smaller scale a modification of the iron con-
nected with a heater or burner for gasifying
fluids.

55 Fig. 5 is a rear end elevational view of
another modification, with closed shutter

and removed heater, with only one burner
outlet, on a smaller scale.

Figs. 6, 7 and 8 are diagrammatical sec-
tions, indicating variations of internal parti-
tion arrangements.

Fig. 9 is a horizontal sectional view, taken
on line 9—9 of Fig. 1.

Fig. 10 is a similar sectional view taken
on line 10—10 of Fig. 1.

Fig. 11 shows a modification of the shutter
and heater.

Fig. 12 shows the last modification with
the shutter down after the heater is re-
moved.

Fig. 13 shows this modification as an ele-
vational view of Fig. 12, and

Fig. 14 shows this modification as an ele-
vational view of Fig. 11.

The apparatus comprises a handle 15,
mounted in a supporting frame 16, curved
and bent so as to present a horizontally dis-
posed part 17, substantially parallel with
the axis of the handle, and secured by bolts
or screws 18 to the iron proper, which, as
indicated, is of the conventional form and
arranged with a number of partitions, di-
viding the interior into a plurality of com-
partments whereby the heat is delivered and
caused to circulate so to avoid loss.

In Fig. 1 is shown a preferred embodi-
ment in which gas enters by means of the
tubes 20, passes through the mixer 21,
where it is regulated by the adjusting screw
22, a proper admission of the air and gas
being provided for by the perforated annu-
lus 23, the combined air and gas being ig-
nited at the end of the curved burner 24,
where it enters the lower central compa-
rtment of the iron. The burner is secured
in a known manner against the back-flare
of the burning gas.

The burner is preferably arranged with
two outlets, and has a neck 25, and is pro-
vided with a suitable connection 26 adapted
to engage with an upturned projection 27
provided on the rear plate 30 of the iron,
the same being held in place normally by
means of the projections 29 on the shutters
28. The rear plate 30 is provided with holes 31
for the burner outlets 24, with the outlets for
waste gases 32, and the inspection opening 33
which is closed by a swinging cover 34. The
solid part of the rear plate 30 being adapted
to close the rear openings of the iron com-
partments, the holes 31 and 32 will be closed

60

90

100

105

110

automatically by means of the shutters 28, which are arranged to swing on the screws 41 engaging with the rear plate 30. It is also possible to connect the waste gas outlet 5 holes 32 with a tube to lead the waste gas to a chimney or the like.

In the form shown in Figs. 1, 2, 3, 9 and 10 preferably a divided burner is used, the heat from which enters the central lower 10 compartment 35, passing upwardly at the front into compartment 36, thence toward the rear through the passage 38, out at the sides, where it is divided, portions passing forward through the compartments 37, again 15 upwardly through the openings 39 into the top compartment 40, and finally outward through the openings 32 into the atmosphere, or a tube to a chimney or the like.

Thus it will be seen that by causing the 20 heat to pass sinuously through the several compartments its full effect is obtained and that the loss by radiation of heat is reduced to a minimum. It will also be seen that the greatest degree of heat is delivered into the 25 lower or heating compartment 35 directly over the smoothing portion of the iron, while the side and top compartments which almost entirely surround the heating compartment act as heat retaining compartments. 30

The openings 32 allow for the proper disposition of the gases in such manner as to least affect the operator, while the iron gets the full benefit of the gas consumed.

In the modifications shown in Figs. 5, 11, 35 12, 13 and 14, the burner is not divided, and has only one outlet which is adapted to engage the burner inlet 31, and one waste gas outlet 32, both openings being covered when 40 the burner is removed by means of a swinging plate 28, connected with the rear plate of the iron by screws 41 in Fig. 5. In this modification a shutter plate 28 is shown closed and having no opening for the waste 45 gas outlet shown in Figs. 3, 11, 12, and 14, although this may also be provided if desired. The position of the plate when the burner is in position is indicated by a broken line, while the broken line indicating the 50 plate in Fig. 3 shows the same in its position when the burner is removed, the inspection opening 33 being shown as covered with a swinging cover 34. A similar adaptation for the heater with only one burner 55 outlet is shown in Figs. 11, 12, 13 and 14, in which the shutter 28 is shown as a plate sliding in slideways 42 and closing the openings 31 and 32 automatically when the heater is removed, and is also adapted to hold the 60 heater in position by means of a hook 26 provided on the heater, and lip 27 provided on the shutter 28, when the heater is attached to the iron.

Figs. 6, 7 and 8 indicate modifications of 65 construction, showing different arrange-

ments of compartments, and the direction of the heat currents therein. Many other modifications with two or more compartments are possible.

Fig. 4 shows a modification in which instead of using a heater with natural or artificial gas, a known arrangement for gasifying fluids is used, which is connected with the flat iron rear plate by the same means and with the shutter and holder hereinbefore 75 described. It will be obvious that the same flat iron can be used with a burner for gas, or with a burner for gasifying fluids, which latter is inclosed in a bulb or container 43 as indicated in Fig. 4, and which contains 80 all necessary means for regulating the control of the liquid, its gasifying and the admission of air to mix with and burn the liquid gas.

From the foregoing it will be seen that a 85 scientifically arranged iron has been presented, which may be used with either gas or gasifying fluids with equal facility, and in which the heat is fully conserved before the waste gas is released into the atmosphere. 90

Having thus described my invention and set forth its application and use, what I claim as new and desire to secure by Letters Patent, is: 95

1. In a device of the class described, the combination with a hollow body constituting a flat-iron and having a number of compartments therein connected with each other to form a continuous passage, the lowermost 100 of said compartments having an exit for the waste gases, of a burner detachably connected with said iron, means for positively engaging said burner with said iron, said means also operating to cover, upon the removal of said burner, automatically the openings in said iron connecting its compartments with the atmosphere, and means for regulating the supply of gas and combustion and heat into the iron. 105

2. In a device of the class described, the combination with a hollow body of metal or the like suitable for the purpose of ironing or smoothing, having gas and air inlet with controlling means therefor on the rear side 110 of the iron only, of a plurality of compartments connected with each other to form a continuous passage for the heating gas, a burner and air entrance in the lowermost of said compartments, an exit for waste gas arranged in the uppermost of said compartments, and means for automatically covering said exit and the burner and air entrance upon the removal of said burner, said means being also operative to engage said 115 burner with said iron.

3. In a device of the class described, the combination with a hollow body of metal or the like suitable for the purpose of ironing or smoothing, a handle operatively en- 120 125

- gaged therewith, partitions arranged horizontally and vertically in said iron, forming compartments therein, said compartments having a communicating means and forming continuously connected flues there-in and having a gas and air entrance in the lowermost compartment which is used as the combustion chamber and from which the heat travels in a continuous way through the next following flue until the waste gas passes the exit port in the uppermost compartment, means for attaching the burner to said iron and entrance for gas and air, and cover plates adapted to open the waste gas exit and gas and air entrance, the operation of said cover plate allowing an attachment of the burner and a closure of the same automatically when said burner is removed and the iron is used with stored heat or out of use and to secure the burner connection with said iron.
4. In a device of the class described, the combination with a hollow compartment body forming a combustion chamber in the lowermost compartment provided with automatically closable gas and air entrance, and surrounding compartments forming continuously connected flues for the travel and utilization of the heating gas until it reaches the waste gas outlet in the uppermost compartment, with a handle and a shutter for automatically closing the burner operation openings and adapted to act also as a connecting means, of a detachable heater for gas and gasifying fluids adapted to permit the use of the same apparatus for different heaters and each of such different heaters for one or more irons, and to use the iron for smoothing purposes while connected with such heater and also to use the closed iron for smoothing or ironing purposes after the iron is heated and the heater removed.
5. In a device of the class described, the combination with a hollow compartment iron, of a handle, an automatic shutter and holder, a detachable heater for gas or gasifying liquids having the highest operative temperature on the bottom of the iron, and means for lessening loss of heat by radiation comprising surrounding compartments connected as continuous flues beginning with the gas and air inlet and ending with the waste gas outlet, said shutter being adapted to automatically closing off the gas and air inlet and the waste gas outlet when the heater is removed.
6. In a device of the class described, the combination with a hollow compartment iron, of a handle, an automatic shutter and holder, a detachable heater for gas or gasifying fluids with burner outlets, means for attaching said heater to said iron connecting its outlet with the gas and air entrance of the combustion chamber of the iron formed by the bottom of said iron above the smoothing surface of the same and the inner walls of the surrounding casing, and continuous flues connecting the other compartments to carry off the combustion gases and having all operation entrances and outlets closed when the heater is detached, substantially as specified and shown.
7. In a device of the class described, the combination with a hollow iron having a series of compartments formed therein and connected as continuously operating flues starting with the gas and air inlet and ending with the waste gas outlet if the burner is attached, operating handle for the iron, a detachable heater adapted to be connected with the iron and its burner inlet with the bottom compartment of the iron, means for holding said heater in operative position upon said iron, and a shutter adapted to open the gas and air inlet and the waste gas outlet and to secure the heater connection when the heater is attached and to close automatically the gas and air inlet and the waste gas outlet of the iron against the atmosphere when the heater is detached.
8. In a device of the class described, the combination with a hollow iron, upper and lower compartments formed in the interior of said iron and opening one into another to permit the passage of heat therethrough from the combustion chamber above the smoothing surface as a continuous connected flue to the closable waste gas outlet, an operating handle, a detachable heater arranged and adapted to connect through the gas and air inlet into the lower compartments of the iron, means for holding said heater in operative position upon its iron, and means for automatically closing the inlets for gas and air and the waste gas outlet of the iron when the heater is detached therefrom.
9. In a device of the class described, a hollow iron having a lower heating compartment adjacent to the smoothing surface of the iron, heat retaining compartments arranged adjacent to said heating compartment, said compartments having intercommunicating openings to permit the passage of heat therethrough in a continuous way from the lowermost compartment so called combustion chamber to the waste gas outlet of the uppermost compartment, an operating handle for said irons, a detachable heater adapted to connect with its outlet with the combustion chamber, means for holding said heater in position, and a shutter adapted to open the gas and air inlet and the waste gas outlet and to secure the heater connection when the heater is attached and to close automatically the air and gas inlet and the waste gas outlet against the atmosphere, forming a heat retainer out of the iron when the said heater is detached.

10. In a device of the class described, a hollow iron having a heating compartment at the bottom part thereof, heat retaining compartments inclosing said heating compartments on all sides except the bottom side thereof, forming a combustion chamber at the bottom of said iron and from these continuously connected flues to the waste gas outlet, a detachable burner arranged to connect with its outlet with the combustion chamber, means for holding said burner in operative position, and means for closing the inlet to said combustion chamber and the waste gas outlet of its surrounding flues automatically when the burner is detached.

11. In a device of the class described, a hollow iron having a heating compartment formed in the lower part thereof, heat retaining compartments formed at the sides and top of said heating compartment, said compartments having intercommunicating means for the passage of heat therethrough forming a combustion chamber at the bottom of said iron and from these continuously connected flues to the waste gas outlet, a detachable burner adapted to connect its outlet with the combustion chamber as the first compartment, a shutter adapted to close the inlet into said heating compartment and the waste gas outlet of the last and uppermost compartment automatically when the burner is removed, interlocking means formed with said burner and shutter adapted to hold said burner in operative position with relation to the iron, said iron having an inspection opening formed in the lower compartment thereof and a cover adapted to close the same automatically when not in use.

burner is attached and interlocking means formed with said burner and shutter adapted to hold said burner in operative position 35 with relation to the iron.

12. In a device of the class described, a hollow iron having a heating compartment formed in the lower part thereof, heat retaining compartments formed at the sides 40 and top of said heating compartment, said compartments having intercommunicating means for the passage of heat therethrough forming a combustion chamber at the bottom of said iron and from these continuously 45 connected flues for allowing the leading off of the waste heat as described and shown, a detachable burner adapted to connect its outlet with the combustion chamber as the first heating compartment, a shutter adapted to 50 close the inlet into said heating compartment and the waste gas outlet of the last and uppermost compartment automatically 55 when the burner is removed, interlocking means formed with said burner and shutter adapted to hold said burner in operative position with relation to the iron, said iron having an inspection opening formed in the lower compartment thereof and a cover adapted to close the same automatically 60 when not in use.

In testimony whereof I have affixed my signature.

F. M. EUGENE BLASS.
